FURNACE

Josef Eberwein, Wilkinsburg, Pa., assignor to
Westinghouse Electric & Manufacturing Com-
pany, East Pittsburgh, Pa., a corporation of
Pennsylvania

Application January 31, 1935, Serial No. 4,286

8 Claims. (Cl. 266—5)

My invention relates to furnaces and particularly to heat treating furnaces.

An object of my invention is to provide a heat treating furnace that shall embody means to insure uniform heating of a charge placed therein.

Another object of my invention is to provide a heat treating furnace that shall embody means to insure a minimum heat loss from a charge to its support.

Another object of my invention is to provide a heat treating furnace that shall embody means to reduce the time of heating up a charge placed therein.

Other objects of my invention will either be pointed out specifically in the course of a description of several forms of furnaces embodying my invention or will be apparent from such description.

In practicing my invention, I provide, in combination with a furnace casing including a base and superposed walls thereover constituting a casing, an extended heating means, either fuel or electric, and particularly one or more heat-insulating pads having high thermal reluctance spaced from a refractory supporting base by a skeleton frame having a small heat conducting area.

In the single sheet of drawing.

Figure 1 is a view in vertical section through one form of device embodying my invention;

Fig. 2 is a view in vertical section through a second form of furnace embodying my invention; and

Fig. 3 is a view on an enlarged scale of a part of a furnace particularly embodying my invention.

I wish it to be understood that the showing of the furnace structures made herein is schematic or general only, insofar as it relates to details other than those comprehended within my invention, and that while specific embodiments of furnaces are shown and described, my invention is not limited to these, but is applicable to any kind of furnace wherein material is to be heat treated while resting upon a supporting base.

Thus the source of heat may be hot gases, a gas flame or an electric resistance heater, and the furnace structure may be of circular shape in cross-section or of rectangular shape, and the furnace in general may either be of the vertical or of the horizontal type.

In the heat treating of material, be it of annular material, such as coils of wires stacked one upon another, or of sheets of metal which may be laid flatwise one upon another or which may be stood

on edge on a support, it has been found difficult to obtain a uniform temperature extending vertically of the mass of material to be heat treated. Particularly is this true in the case of the so-called "bell type" furnace, in which a substantially fixed refractory base structure may be used and in which the bell-like cover carrying the electric heating elements is movable, as by a crane, so that, as soon as one charge, which may be covered with a thin-sheet-metal hood, has been treated to the desired temperature, the furnace casing or cover may be removed therefrom and immediately placed over a cold charge located on another base. It is obvious that if the material to be heat treated rests directly on the base, a large amount of heat will flow downwardly into the base from the material as its temperature is raised, and I have found that it is possible to overcome this excessive loss of heat downwardly by the use of a skeleton frame resting upon the base and in turn supporting the material to be heated.

Referring first to Fig. 1 of the drawing, I have there illustrated a furnace structure 11 shown as comprising a refractory base 13 resting upon a metal base plate 15, which in turn is supported as by structural metal members 17 of any desired kind. However, as my invention is not limited to fixed bases, the base 13 may be provided with wheels or rollers to permit of its being moved from one place to another, if desired. The base 13 is provided with a raised central portion 19 and with a lower outer annular portion 21 for a purpose to be hereinafter set forth.

A bell-shaped cover 23 includes an outer metal casing 25, which may be of substantially circular shape in contour in the case of a circular furnace, or which may be of rectangular or square shape as may be desired. The casing structure 25 has located therein a refractory lining which is here designated generally by the numeral 27, and which is to be understood as being built up either as a monolith or of suitable bricks or blocks of high temperature resisting and heat-insulating material in a manner well known in the art. This lining 27 is adapted to be held in the shell 25 by metal structural members 29 suitably secured to the lower edge of casing 25. Means for lifting the entire casing may be constituted by one or more horizontally extending cross bars 31 and one or more lifting lugs 33. These details are shown for purposes of completely illustrating a furnace structure, but form no part of my invention.

Heating means for the purpose above described is provided in the form of a plurality of resistor elements 35, 37, 39 and 41, which may be of the

35

40

45

50

55

- kind disclosed and claimed in Patent No. 1,490,732 to T. F. Callaghan. It is to be noted particularly that any desired distribution of heat may be obtained within the furnace chamber 43 by suitable design of the resistor elements 35 to 41, inclusive, which are to be considered as extending entirely around the inner periphery of the wall enclosing the furnace chamber in a manner well known in the prior art.
10. Upon the raised central portion 19 of the base, I locate a skeleton frame structure 45 which includes, in addition to an upper and a lower thin metal plate 47 and 49, vertically extending perforated webs 51 to provide a structure having sufficient strength to support relatively heavy loads, while at the same time having a minimum heat storage capacity and a relatively high thermal reluctance against flow of heat vertically therethrough. Immediately above the upper metal plate 47, I provide a layer or pad 53 of substantially solid heat-insulating material having a relatively high thermal reluctance and having sufficient mechanical strength to support the load of material superposed thereon to be heat treated in the furnace. For this reason, I preferably make the pad 53 of substantially solid heat-insulating material.
- While the use of one skeleton frame structure and one pad of heat-insulating material thereabove may be sufficient in some cases, I have found it desirable, under certain conditions, to provide two such sets of elements, and, as shown in Fig. 1 of the drawing, I may provide a second skeleton frame 54 including a lower plate 55, an upper plate 57, and a plurality of perforated webs 59 therebetween of the same general design as was hereinbefore described for the lower skeleton frame 45. A second pad 61 of heat insulating material having a high thermal reluctance is located above the upper plate 57, and a metal plate 63 rests upon the pad 61 to directly support a mass of annular material 65 which may be, for instance, coils of wire to be heat treated in the furnace.
- As it may happen that moisture may have condensed on the untreated material 65, which moisture may deleteriously affect the material of the pads 53 and 61, the plates of the skeleton frames may be provided with vertically extending flange portions 67 integral therewith which may be secured together over substantially, but not entirely, the entire peripheral surface to substantially enclose the pads, a small opening being provided to permit the moisture to escape from the pads upon heating up thereof.
55. As it may be desirable to protect the material 65 against oxidation, as may be necessary for certain classes of material, I may provide a thin sheet metal hood 69 of substantially annular shape and of sufficient diameter to enclose the material 65 and to fit within the heating elements herein described. The hood 69 is further provided with a horizontally-extending flange 71 and a depending flange portion 73 thereon which fits into an oil or sand seal 75 provided at the outer periphery of base plate 15. Means for introducing a neutral gas may comprise an inlet pipe 77 extending centrally upwardly through the base 13 and with its upper end located closely beneath the top of the domed hood 69, any gas entering the furnace chamber being caused to flow radially outwardly and then downwardly, as indicated by the arrows 79, and through outlet pipes 81. It is to be understood that the furnace structure, either circular, square or rectangular in cross section, is such as to provide a substantially

completely enclosed furnace chamber defined by the base and either the hood, or if the same is not necessary and, therefore, not used, by the furnace casing, as hereinbefore described.

While I have shown the lower edge of the furnace casing as resting upon the flat annular portion 71, I do not desire to be limited thereto, since the furnace casing may rest upon a support other than the base, but it is necessary that a substantially air-tight furnace chamber structure be provided.

In operation, a plurality of bases 13, either fixed or movable, may be provided, and a lesser number of bell-like furnace casings, so that as soon as a charge 65 located on a base has been heated to the desired temperature, the furnace casing with its associated heater may be removed and immediately located on a cold charge resting upon a second similar base.

When the hot furnace casing is placed upon or in operative relation to the base with its cold charge, a large amount of heat will be absorbed by the cold base, as well as by the cold charge, and if no heating pad or pads and the associated skeleton frame or frames were provided, a relatively large amount of heat would flow downwardly into the base. The heating element is, of course, immediately energized as soon as the proper positioning of bell-like furnace casing 23 on the base 13 has been effected, and if no heat insulating pads whatsoever are provided, a relatively large amount of heat from the charge while it is being heated would continue to flow downwardly into the refractory base particularly, for instance, if the charge 65 were to be located directly upon and in contact with plate 49, assuming this to have been provided to protect the refractory structure 13.

If, for instance, a thermo-couple is placed in the upper portion of charge 65 in order to determine when the charge has been heated to the desired temperature, it may happen that the temperature of the lower portion of the charge is much lower than that of the charge where the thermo-couple is located, if no heat insulating pad or pads and skeleton frame or frames are provided. This loss of heat is deleterious for several reasons, one of which is, as has just been stated, that the temperature of the material being heat treated is not uniform from top to bottom of the mass, and secondly, that a much longer time is required to insure that all of the material being heat treated has been raised to substantially the same desired temperature.

However, by the use of my invention including at least one skeleton frame structure having a high thermal reluctance to the flow of heat therethrough and at least one pad of heat insulating material, preferably solid, and also having high thermal reluctance, I have found it possible to heat a mass of material to a temperature on the order of 1500° F. with a maximum variation of temperature from top to bottom of the mass of approximately 5° F. This compares with a figure of 100° F. or even more when no insulating pad or skeleton frame is used.

I attribute this result not only to the use of at least one pad and skeleton frame work, but also to the fact that a part of the heat means is located in substantially the same horizontal plane as are the skeleton frames which, as was hereinbefore stated, are of open construction and, as will be noted from Fig. 1 of the drawing, the lower one may be of greater vertical height than the upper one. Thus heating element 41 is

located in substantially the same horizontal plane as skeleton frame 45 and will heat the same through the hood 69, or will heat not only the frame but also any air or gas located therein, to such an extent, that its temperature will be but slightly below that of the mass 65. The same comments hold good with regard to heating element 39, which is located in substantially horizontal alignment with the upper skeleton frame, so that it and any air or gas located therein will be subjected to radiated heat to thereby cause the temperature thereof to almost equal that of the mass 65 being heat treated. I, therefore, provide at least one horizontally extending zone of high temperature located between the bottom of a mass of metal being heat treated and a base, which is highly effective in preventing appreciable loss of heat in a downward direction. It is therefore possible, when using my invention, to reduce the number of bases and of covers below the number which would be required to obtain the same output, while at the same time obtaining a more uniformly heat treated product.

Referring now to Fig. 2 of the drawing, I have there illustrated a modified form of furnace structure embodying my invention. A furnace 91 includes a refractory base 93 resting upon a base plate 95 which is supported by a plurality of structural beams 97. The base includes, in addition to the raised central portion 93, a lower outer peripheral portion 99, which latter may be provided with a sand or oil seal structure 101 in a manner well known in the art.

A skeleton frame structure 103 rests upon the central annular portion 98, which latter may be covered by a thin sheet metal member 105 to protect the same against the influence of moisture or other deleterious agents. The frame 103 is substantially the same, in general design, as the other skeleton frames herein described in connection with Fig. 1 of the drawing, in that it provides the necessary mechanical strength with a minimum amount of heat-absorbing or heat-transmitting material.

A pad 107 of heat insulating material is located on the upper face of frame 103 and may be covered by a thin sheet metal casing 109 which is substantially entirely closed except for a small opening to permit the escape of moisture during operation of the furnace. Means for supporting a charge 110 on the metal encased pad 107 may be constituted by a plurality of segmental metal plates 111 or by a single metal plate as may be desirable or necessary.

The charge 110 may be covered by a thin sheet metal hood 113 which has, in addition to an outer wall 115, an inner wall 117 adapted to surround a central axial heating element 119.

A furnace casing 121 is of substantially the same design as was hereinbefore described for the casing 23, that is, it includes an outer metal shell 123, a refractory lining 125 therein, from which wall lining a plurality of annular heating elements 127, 129, 131 and 133 are adapted to be supported, these heating elements being the same as were hereinbefore described in connection with the furnace structure shown in Fig. 1 of the drawing. The furnace casing 121 is provided with a plurality of horizontally extending beams 135 and cross beams 136 having one or more lifting lugs 137 thereon, the central heater 119 being supported from a beam 135.

Means for introducing a neutral or non-oxidiz-

ing gas under the hood 113 may comprise an inlet pipe 139 which ends just below the central portion of the hood 113 the gas flowing upwardly inside of the hood and between wall 117 and the charge 110 and then downwardly on the inside of outer wall 115 and outwardly through one or more outlet pipes 141. The outer wall 115 of the hood has a flat annular flange 143 secured thereto which ends in a depending annular flange 145 adapted to fit into the seal structure 101.

Since it is desired that the gas entering through the pipe 139 flow upwardly into the upper end portion of the hood and then downwardly, I may provide a suitable thin metal closure member 147 secured to the inner periphery of the skeleton frame 103 to close off any possible outlet of the gas, and it is noted that the vertical webs of frame 103 may be solid or perforated while the vertical webs 51 and 59 (Fig. 1) may be perforated, as has already been pointed out.

The operation of the furnace structure shown in Fig. 2 of the drawing is substantially the same as was hereinbefore set forth in Fig. 1 of the drawing, and, therefore, need not be repeated.

In Fig. 3 of the drawing, I have illustrated, on an enlarged scale, one form of heat insulating pad 151 which comprises a bottom sheet metal wall 153 of dish-shape and an upper sheet metal wall 155 also of dish-shape whose annular edges may meet to enclose the pad 157 of refractory heat-insulating material having not only a low thermal capacity but having also a high thermal reluctance. A charge to be heat treated and to be supported upon the pad structure 151 may rest directly upon a plurality of metal plates 159 having inner depending flanges 161 fitting into a well 163 in the upper sheet metal member 155. An inlet pipe 165 comparable to inlet pipe 77 may extend upwardly through a central opening 167, and in order to hold the plurality of segmental plates 159 in their proper operative and relative positions, I may provide an annular member 169 centrally perforated to permit of pipe 165 extending therethrough.

The device embodying my invention is, as has already been hereinbefore set forth, applicable to any kind of furnace structure irrespective of whether the casing of the furnace is vertically removable from the base or not, and while I have shown two furnace structures with a substantially fixed base and a removable cover thereover, my invention is not to be considered as being limited thereto, since the furnace cover or casing may also be located in substantially fixed position relatively to the base. It is obvious also that a plurality of spaced pads may be located in the same horizontal plane instead of only a single pad.

As has already been hereinbefore set forth, I have found it possible, by the use of the heat insulating pads and the skeleton frame structures embodying my invention, to insure substantially uniform heating of a relatively high stack of material so that the temperatures of the different parts thereof will be substantially the same.

I have found it possible also to operate a furnace of this kind more economically not only as to consumption of gas, fuel or electric energy, but also to obtain quicker heating up and, therefore, a greater economy in the use of the furnace, since it is possible to obtain a much greater output from a given furnace or from a given number of furnaces than would otherwise be possible.

Various further modifications may be made in the device embodying my invention without departing from the spirit and scope thereof, and I

desire, therefore, that only such limitations shall be placed thereon as are imposed by the prior art or are set forth in the appended claims.

I claim as my invention:

5. 1. A heat treating furnace comprising in combination, a flat base, a furnace casing thereabove cooperating with the base to enclose a metallic charge supported on the base, a skeleton frame work having a relatively low thermal conductivity on the base, a metal-bound layer of substantially solid heat-insulating material having high thermal reluctance on the skeleton frame work directly operatively supporting a charge to be heat treated, and an extended electric heating means in the furnace casing for heating the charge and having a bottom section thereof located below the plane of said layer to supply heat to the skeleton frame and the bottom of the layer of solid heat-insulating material.
10. 2. An electric furnace comprising in combination, a substantially solid flat base, a furnace casing thereabove and cooperating with the base to provide a furnace chamber to contain a metallic charge, a metal-bound pad of heat-insulating material of high thermal reluctance directly operatively supporting a charge to be heat treated, a plural-section electric heating unit within the furnace casing to supply heat to a charge therein and means providing a high temperature zone between the pad and the base, comprising a lower section of the heating unit disposed below the plane of said pad and a hollow frame supporting the pad on and spacing it from the base.
15. 3. An electric heat treating furnace comprising in combination, a substantially flat base, a furnace casing, of bell-shape, above the base and cooperating therewith to enclose a furnace chamber, a skeleton frame of low heat storage capacity and high thermal reluctance on the base, a metal-bound pad of substantially solid heat-insulating material on the skeleton frame and adapted to directly operatively support a metallic charge to be heat treated, and an extended electric resistor heater supported by the casing adjacent its inner surface and having a complete section located in substantially the same horizontal plane as the skeleton frame to heat it and any gas located between the base and the pad to provide a high temperature zone below the pad.
20. 4. An electric heat treating furnace comprising in combination, a substantially flat base of solid refractory material, a removable furnace casing, of bell-shape, above the base and cooperating therewith to enclose a furnace chamber, a skeleton frame, of low heat storage capacity and high thermal reluctance, on the base, a metal-bound pad of substantially solid heat-insulating material of high thermal reluctance on the skeleton frame and adapted to directly operatively support a metallic charge to be heat
25. treated in the furnace chamber and an extended electric resistor heater supported by the furnace casing adjacent to the charge to heat the same and having a segregated section specially located to heat as a unit the skeleton frame and any gas located between the base and the pad to provide a high temperature zone below the pad and thereby reduce heat flow from a heated charge to the base.
30. 5. An electric furnace comprising in combination, a base on which material to be heat-treated is located, a casing enclosing the material, heating means within the casing, and a metal-bound pad of heat-insulating material having high thermal reluctance located between the base and the material, said pad having an opening therethrough for permitting the passage of a gas for treating said material.
35. 6. An electric furnace comprising in combination, a substantially solid base, a furnace casing thereabove and cooperating with the base to substantially enclose a charge to be heat treated in the furnace, an electric heating element within the casing, a skeleton frame work on the base, a metal-bound layer of substantially solid heat-insulating material of high thermal reluctance between the charge and the skeleton frame work, and means for conducting a neutral gas through said layer to the charge.
40. 7. A heat treating furnace comprising in combination, a flat base, a furnace casing thereabove cooperating with the base to enclose a charge supported on the base, a skeleton frame work having a relatively low thermal conductivity on the base, a metal-bound layer of substantially solid heat-insulating material having high thermal reluctance on the skeleton frame work directly operatively supporting a charge to be heat treated, an extended heating means in the furnace casing for heating the charge and having a bottom portion thereof located to supply heat to the skeleton frame and the bottom of the layer of solid heat-insulating material, and means for conducting a neutral gas through said layer to the charge.
45. 8. An electric furnace comprising in combination, a substantially solid flat base, a furnace casing thereabove and cooperating with the base to provide a furnace chamber to contain a charge, a metal-bound pad of heat-insulating material of high thermal reluctance directly operatively supporting a charge to be heat treated, a plural-section electric heating unit within the furnace casing to supply heat to a charge therein and means providing a high temperature zone between the pad and the base, comprising a lower section of the heating unit and a hollow frame supporting the pad on and spacing it from the base, said pad having an opening therethrough for permitting the passage of a gas for treating said material.

JOSEF EBERWEIN.
